CLAIM

The ornamental design for a snorkel for child, as shown and described.

DESCRIPTION

FIG. 1 is a perspective view of a snorkel showing my new design;

FIG. 2 is a front elevation view thereof;

FIG. 3 is a right side elevation view thereof, the left side view being a mirror image of the right side view; and, FIG. 4 is a top plan view thereof.

The broken lines in the drawings illustrate portions of the snorkel that form no part of the claimed design.
